COMBINED STEREO TAPE PLAYER RECEIVER AND DIGITAL CLOCK

Michio Tatsuta, Tokyo, Japan, assignor to Tokyo
Trading Co., Ltd., Tokyo, Japan

Filed Mar. 8, 1973, Ser. No. 339,253

Term of patent 14 years

Int. Cl. D14—03; D10—01
U.S. Cl. D26—14 B

FIG. 1

FIG. 2

FIG. 3

FIG. 4

FIG. 5

FIG. 6

FIG. 1 is a front elevation view of the receiver with digital clock of a combined stereo tape player receiver and digital clock embodying my new design;

FIG. 2 is a rear elevational view thereof;

FIG. 3 is a top plan view thereof;

FIG. 4 is a bottom plan view thereof;

FIG. 5 is a right side elevational view thereof; and FIG. 6 is a left side elevational view thereof.

I claim:

The design for a combined stereo tape player receiver and digital clock, as shown.
